UNITED STATES PATENT OFFICE

CHARLES DAVIS LITTLE, OF CHATTANOOGA, TENNESSEE

DESIGN FOR A BOTTLE

Application filed February 5, 1929. Serial No. 29,942. Term of patent 14 years.

To all whom it may concern:

Be it known that I, CHARLES DAVIS LITTLE, a citizen of the United States, residing at 16 East 14th St., city of Chattanooga, in the county of Hamilton and State of Tennessee, have invented a new, original, and ornamental Design for Bottles, of which the following is a specification, reference being had to the accompanying drawing, forming part thereof.

The figure is a side view in elevation of a bottle, showing my new design.

I claim:

The ornamental design for a bottle, as shown.

CHARLES DAVIS LITTLE.
